UNITED STATES PATENT OFFICE.

GEORGE W. COPE, OF DETROIT, ASSIGNOR TO HUGH L. SMITH, OF JACKSON,
MICHIGAN.

DESIGN FOR A STOVE.

SPECIFICATION forming part of Design No. 22,189, dated January 31, 1893.

Application filed July 12, 1892. Serial No. 439,827. Term of patent 3½ years.

To all whom it may concern:

Be it known that I, GEORGE W. COPE, a citizen of the United States, residing at Detroit, in the county of Wayne and State of Michigan, have invented a new and original Design for Stoves, of which the following is a specification, reference being had therein to the accompanying drawing, showing the same in perspective.

10 A is a roller-supported ring forming a rolling base for the stove. The base proper consists of an ornamental ring B having the lower scalloped edge C, an upper ring D ornamented by a scroll design, as shown at E and an 15 interposed cylindrical casing F, this is likewise ornamented.

G are legs having an upward extension H extending from the lower ring B to the upper ring

D crossing the face of the cylindrical casing F and dividing that casing into panels formed 20 between the raised extensions of the legs, which are ornamented with a scroll design. The top consists of the globe shaped combustion chamber I, the cylindrical casing J and the ornamental top K.

25 The essential feature of the design is the base of the stove.

What I claim as my invention is,

The design for a stove substantially as 30 herein shown and described.

In testimony whereof I affix my signature in presence of two witnesses.

GEORGE W. COPE.

Witnesses:

M. B. O'DOGHERTY,
N. L. LINDOP.
